(57) **CLAIM**

The ornamental design for an automobile, as shown and described.

DESCRIPTION

1. Automobile

1.1 : Perspective

1.2 : Front

1.3 : Back

1.4 : Left

1.5 : Top

The broken lines depict portions of the automobile that form no part of the claimed design; the fine lines on the drawings indicate the curved surface and display part; reproduction 1.1 is a front perspective view of the automobile; reproduction 1.2 is a front view thereof; reproduction 1.3 is a back view thereof; reproduction 1.4 is a left view thereof where the right view is a mirror image; reproduction 1.5 is a top view thereof; the bottom view is omitted since that cannot be seen in use; this design also has a transparent display at the front.
